INVENTOR:
HENRY BASCOM

BY Harry. Barnes
ATTORNEY.

UNITED STATES PATENT OFFICE

2,658,225

SHOESHINE STAND

Henry Bascom, St. Louis, Mo.

Application March 27, 1950, Serial No. 152,081

2 Claims. (Cl. 15—265)

1

My invention has relation to improvements in shoe-shining stands and it consists in the novel features of construction more fully set forth in the specification and pointed out in the claims.

The principal object of the invention is to provide a stand that is collapsible and portable when not in use but may be easily extended and solidly positioned for use by the operator. A further object is to provide a foot-rest adjustable for patrons of varying leg lengths to insure comfort and relaxation while being served. It is also an object to provide a secure locking mechanism for the supply drawer that is hidden from the view of an observer.

These objects together with other advantages of the invention will be better apparent from a detailed description of the invention in connection with the accompanying drawings, in which:

Figure 1 is a side elevation of my improved shoe-shining stand extended for use; Figure 2 is a front elevation thereof; Figure 3 is a top plan of the same; Figure 4 is a side elevation of the stand collapsed for portability; Figure 5 is a vertical section taken on the line 5—5 of Figure 3 with parts broken away; Figure 6 is a horizontal section taken on a plane indicated by the line 6—6 of Figure 5; Figure 7 is a horizontal section taken on the line 7—7 of Figure 1; Figure 8 is a horizontal sectional detail taken on the line 8—8 of Figure 7; Figure 9 is a cross-sectional detail taken on the line 9—9 of Figure 7; Figure 10 is a sectional detail taken on the line 10—10 of Figure 5; Figure 11 is a cross-sectional detail taken on the line 11—11 of Figure 1; and Figure 12 is a cross-sectional detail taken on the line 12—12 of Figure 8.

Referring to the drawings, F represents a stool frame comprising legs 1, 1 and 2, 2 connected by arm rests 3, 3 and having a back and seat frame F' secured to it by welding. A seat 4 is supported by seat member 5, and a back-rest 6 is affixed to back member 7. If desired an umbrella 8 may be supported over the entire shoe-shining stand by a frame 9 carried in sockets 10, 10 fixed to the posts or legs 2, 2.

There is an angle iron band 11 welded to the legs 1, 1 and 2, 2 to reinforce the frame F and a brace 12 extends from one side of the band 11 to the other. A centrally disposed rail 13 is secured at its ends to brace 12 and band 11 for a purpose that will presently appear.

A box 14 is positioned for movement back and forth between the legs 1, 1, said box having a channel member 15 fixed on each side by suitable screws 16 for receiving a pair of rollers 17, 17

2

mounted in spaced relation on each leg 1. It will be observed that the forward portion 15' of each channel member 15 is inclined upwardly so that when the box 14 is moved inwardly the rollers 17, 17 will roll upwardly in the channel 15' and raise the legs 1, 1 off the floor. Of course there are casters 18, 18 at the forward end of the box 14 so the box has complete rolling support. The box 14 has a rear compartment 19 formed by a partition 20 and bottom 21 at the rear of box 14, which compartment may be closed by a lid 22 hinged to rear wall 23 of box 14. On the inside surface of lid 22 is a mirror 24 and a sliding brace 25 of well known construction holds lid 22 open in any desirable position so the operator may see the backs of his customers shoes, or any one approaching behind him.

A pair of foot-rests 26, 26 are carried by standards 26', 26' mounted on the top 27 of box 14, said foot-rests being sufficiently spaced to permit an operator's seat 28 to be swung rearwardly between them on the hinges 29, 29 fixed adjacent to the front edge of box top 28. The seat 28 is mounted on a seat frame 30 formed in the shape of a U, the ends of which terminate in hinge leaves 31, 31 forming a part of hinges 29, 29. A strut 32 is secured (preferably by welding) to the apex of the U-frame 30 for supporting the forward part of the seat. Figure 4 shows the position of seat 28 when folded back out of use.

It will be observed that a bracket 33 is mounted on the outer surface of rear wall 23 of box 14 and has a roller 34 mounted midway between its side members 35, 35. This roller 34 supports the inner end of box 14 on rail 13 as the box is moved inwardly beneath the stool frame F, and finally drops into a recess 36 at the rear end of the rail 13 when the box has reached its fully collapsed position.

Within box 14 (which is open at the front) is a drawer 37 (for needed supplies) said drawer being supported by means of a pair of bars 38, 38, one on each side wall 39 of drawer 37. Each bar 38 is mounted in spaced relation from side wall 39 by spacing washers 40 and screws 41 (Figures 8 and 12).

The bars 38, 38 are confined and slidable between two spaced rows of rollers 42, 42 etc. bearing between a plate 43 and opposing flanges 50 44 formed thereon. The plates 43, 43 are carried by side walls a, a of box 14 and extend only to the partition 20 while the bars 38, 38 pass with clearance through slots 45, 45 into compartment 19 when drawer 37 is closed (Figures 5 and 7). When the drawer 37 is fully closed wedge-shaped

detents 46, 46 fixed to the inside surfaces of the box side walls *a*, *a* engage notched formations near the ends of bars 38, 38 whereby the drawer 37 is locked in closed position. Thus when a padlock *P* is placed on lid 22 the entire box 14 is 5 securely locked.

There is sufficient spring in the bars 38, 38 to easily disengage them from detents 46, 46 when drawer 37 is to be opened.

From the foregoing it should be apparent that 10 my improved shoe-shining stand not only is readily portable, but is also quickly adjustable for patrons of varying sizes. In addition the combination lid and rear view mirror facilitates the operator's work, and the novel locking device 15 makes for simplicity.

Having described my invention, I claim:

1. A shoe-shining stand comprising a stool frame, a box slidingly connected to said frame and having independent rolling support, a pair 20 of foot-rests mounted on said box, and means on the box in cooperative relation with the frame for raising the front of the frame when the box is moved into close relationship with the frame.

2. A shoe-shining stand comprising a stool 25 frame, a box slidingly connected to said frame

and having independent rolling support, a pair of foot-rests mounted on said box, and means on the box in cooperative relation with the frame for raising the front of the frame when the box is moved into close relationship with the frame, said means for raising the frame also embodying adjustment for varying the length from seat to foot-rest.

HENRY BASCOM.
